AUTOMATICALLY CLOSING DUSTBIN

Edward J. Galotta and Michael Di Paola,
Bronx, N. Y.

Application April 16, 1948, Serial No. 21,396

6 Claims. (Cl. 15—104)

1

This invention relates to dust bins or dust receptacles, and to containers in which mops may be shaken to remove the dust from the mop and more particularly to dust bins for shaking dust from mops to avoid shaking the mop out of the window or elsewhere where the dust would be objectionable, though it is noted that in some of the claims the invention is not limited to dust bins.

Objects of the invention are to provide an improved closure means for the dust bin and to provide automatic means for closing and opening the closure means.

Other objects of the invention are to provide improved baffles within the bin, and improved means for removing the dust from the bin.

Additional objects of the invention are to effect simplicity and efficiency in such dust bins and to provide an extremely simple dust bin of this kind which is convenient, durable, clean and reliable in operation, and easy to operate and economical to manufacture.

Still other objects of the invention will appear as the description proceeds; and while herein details of the invention are described in the specification and some of the claims, the invention as described in the broader claims is not limited to these and many and various changes may be made without departing from the scope of the invention as claimed in the broader claims.

The inventive features for the accomplishment of these and other objects are shown herein in connection with a dust bin which briefly stated, includes a container having a top wall and a curved side wall, said top wall having a stationary slot extending inwardly from the periphery, said side wall having below said slot a large opening communicating with said slot. A rotary plate or disk rotatably mounted on the top wall carries an apron engaging said curved wall and adapted to close or clear said opening when the plate is partially rotated. Said disk is provided with a curved slot having its outer end registerable with the outer end of the stationary slot when the apron is in open position and its inner end registerable with the inner end of the stationary slot when the apron is in closed position.

When the apron is in open position, a mop and its handle may be inwardly moved through said opening and the slots respectively, whereupon the handle may be pushed to the inner end of the stationary slot causing the camming of the han-

2

dle on the edge of the curved slot and the closing of the apron over said opening, whereupon the handle may be shaken to agitate the mop in the barrel to remove dust therefrom. Outward lateral movement of the mop automatically opening the apron for the removal of the mop.

Gratings and baffles within the container against which the mop may be used, assist in removing dust and dirt from the mop to be removed from the container as explained hereinafter.

In the accompanying drawing showing, by way of example, one of many possible embodiments of the invention:

Figs. 1 and 2 are respectively front elevation and plan showing the dust bin in closed position;

Figs. 3 and 4 are respectively front elevation and plan showing the dust bin in open position;

Fig. 5 is a horizontal sectional view, partly in elevation and drawn to a larger scale, showing the dust bin in open position, the section being taken substantially on the line 5—5 of Fig. 6, looking in the direction of the arrows of said line; and

Fig. 6 is a vertical sectional view, partly in elevation showing the rear part of the interior of the dust bin, the section being taken substantially on the line 6—6 of Fig. 5, looking in the direction of the arrows of said line.

This invention is shown embodied in an automatically closing dust bin for mops, said dust bin comprising a cylindrical bin or barrel 10 having a circular top wall 11 (Fig. 6), a cylindrical side wall 12, upper and lower gratings 13, 14 and uncrossed parallel bars 15, 16 spaced from the top wall and the bottom plane of the barrel respectively and respectively mounted on the interrupted ring 17 and the complete ring 18 supported by brackets 19 welded, soldered or otherwise secured to the side wall 12.

A dust receiving tray 20 in which said barrel rests has a shallow upstanding peripheral wall 21 in which the lower part of the barrel removably rests. A radial outlet nozzle 22 mounted on and projecting from the side wall 12 communicates with the barrel below the lower grating, the wall 21 of the tray having a cut-away notch 23 receiving the nozzle. The nozzle is adapted to receive a hose 22a establishing communication between the interior of the barrel below the lower grating and the suction of a vacuum cleaner or other source of suction for removing the dust from the

barrel. Obviously this nozzle may be omitted, and dust emptied by removing the barrel from the tray and emptying the dust from the tray. The tray bottom may be secured to the side wall 12 if desired, and the tray wall 21 omitted.

The circular top wall 11 is provided with a substantially radial slot 25 wide enough to receive a mop handle 26a and extending through the peripheral edge of the top wall and extending near and offset from the center of the top wall. The side wall 12 of said barrel has below the outer end of the slot 25 a large opening 27 (Figs. 3 and 5) in the front part of the barrel, large enough to admit the mop 26 and extending to near and below the top wall to provide an upper strengthening flange 28 joining the top wall and having an upper vertical slot extension 29 communicating with said slot 25 and large enough to admit the mop handle 26a to said slot 25.

A pivot pin, eyelet or rivet 30, secured in the center of the top wall rotatably receives a peripherally projecting rotary disk 31 on the top wall and having a central opening rotary on said pin 30. The disk 31 may be cut away at the chain line 32, or otherwise designed, to save material.

Said disk 31 carries a closure apron 35 secured on the periphery of said disk and engaging the side face of the barrel and adapted to completely close said large opening 27 when the disk and apron are in one position of rotation shown in Figs. 1, 2 and 5 and to clear said opening when the disk and apron are in a second and open position of rotation as shown in Figs. 3 and 4. Said disk is provided with an at least partially curved or spiral slot 36 wide enough to receive the mop handle 26a and having its inner end registerable with the inner end of the slot 25 when the disk and apron are in closed position as in Fig. 2 and having its outer end registerable with the outer end of the slot 25 when the apron and disk are in said second and open position, as shown in Figs. 3 and 4, whereby said outer ends may receive the mop handle 26a, whereupon the handle 26a may be pushed to the inner end of the slot 25 causing an edge of the curved or spiral slot 36 to cam on the handle until the handle reaches the inner end of the slots, causing partial rotation of the disk and registration of said inner ends and the closing of the apron 35 over said large opening 27, whereupon the handle 26a may be shaken to agitate the mop 26 in the barrel to remove dust therefrom while the dust is confined in the barrel by the apron and disk, and is free to drop through the grating 14 to the lower part of the barrel to be drawn through the nozzle into the hose 22a connected to the suction of a vacuum cleaner or to be emptied by removal of the tray 20, or otherwise removed.

After the dust has been removed from the mop, outward movement of the handle 26a to the periphery of the top wall 11 again causes registration of said outer ends of the slots 25, 36, thus opening the front opening 27 and allowing removal of the mop.

A guide strip 39 is secured around the side wall just below the large opening and having its upper margin slightly outwardly off-set to provide a track-groove 40 (Fig. 5) in which the lower edge of the apron 35 slides and is guided; and a stop strip 41 secured to the side wall near and spaced from the edge of the large opening to which the door moves when closing and has

its margin nearest the opening off-set from the side wall to provide a keeper groove 42 in which the adjacent edge of the apron is received and stopped when in closed position. Said strips 39, 5 41 serve to keep the apron securely closed when the mop is being agitated in the barrel. A stop bracket 43 is secured on the outer face of the barrel in position to stop the apron in fully open position.

10 A half-sleeve 44 large enough to receive half of, and guide, the mop handle has a lower outwardly flange 45 secured to the disk around the inner end of the spiral slot and positioned to allow the sleeve to be substantially coaxial with and to engage and guide the mop handle just out of contact with the inner end edges of the slots. Downwardly projecting horizontal spaced strengthening bars 46' of angular cross-section are secured to said flange 28 and said top and side walls for strengthening the top wall.

15 Inwardly projecting parallel spaced arcuate baffles 46 of round cross-section are mounted on brackets 47 secured to said side wall, the baffles terminating at said large opening 27. Said baffles 46 and gratings 13, 14 facilitate removal of dust from the mop when the latter is beat and rubbed against the baffles and gratings. The upper grating 13 serves to protect the top wall.

20 A pair of plate-like foot rests 48 secured to the lower part of the tray and projecting to lie flat on the floor or other support supporting the tray are adapted to be stepped on by the operator for holding the barrel while the mop is being manipulated or when the barrel is removed from the tray; and handles 49 in the side of the barrel facilitate handling the dust bin and removing the barrel from the tray.

25 The various parts of the dust bin may be held together by welding, soldering or in any suitable known manner.

30 The operation of the dust bin will be easily understood from the foregoing, and is now only briefly summarized as follows:

35 With the bin assembled in open position, as in Fig. 2, the operator merely places the mop to be cleaned approximately in the position of the dotted lines of Fig. 6 with an intermediate part of the handle in the registering outer ends of the slots 25 and 36 and the space 50 (Fig. 5) between the ends of the interrupted ring. Then the upright handle is forced inwardly to the inner ends of the slots 25, 36 and between adjacent bars 15a of the upper grating, the bars 15a being parallel to the slot 25, and connected by a curved cross bar 51 just beyond the inner end of the slot 25. The stated inward movement automatically closes the apron 35.

40 The mop 26 and handle are then agitated and shaken up and down and around at the same time hitting and rubbing the mop upon the un-crossed grating bars 15 and 16 and baffles 46, to remove the dust and dirt and allow them to fall within the tray 20 to be removed as hereinbefore stated. Afterwards, the mop handle is drawn to the outer ends of the slots 25, 36, thus automatically removing the apron from the opening 27, allowing removal of the mop.

45 The bars 15, 16 and baffles are parallel and un-crossed to more readily facilitate removal of dust from the mop, and are spaced from other structure to avoid a place of lodgement in inaccessible places.

50 During the various movements of the mop, the duster may be held stationary by placing the 75 feet on the foot rests 48.

Other forms of mop or other articles which need agitation in a closed container may be used.

The invention claimed is:

1. A dust bin comprising a container having a top wall and a curved side wall said top wall having a stationary slot extending inwardly from the periphery; said side wall having below the slot a large opening communicating with said slot; a rotary plate rotatably mounted on the top wall; an apron secured to said plate and engaging said curved wall and adapted to close or clear said opening when the plate is partially rotated; said disk being provided with a partially curved slot having its outer end registerable with the outer end of the stationary slot when the apron is in open position and its inner end registerable with the inner end of the stationary slot when the apron is in closed position.

2. In combination, a barrel having a circular top wall having a wide approximately radial slot wide enough to receive a mop handle and extending through its peripheral edge to near the center of the top wall; said barrel having below the outer end of the slot a large opening in the front part of the barrel, large enough to admit a mop and extending to near and below the top wall to provide an upper strengthening flange joining the top wall and having an upper vertical slot extension communicating with said slot and large enough to admit the mop handle to said slot; a pivot pin secured in the center of the top wall; a disk on the top wall and mounted for rotation on said pin; an apron secured to said disk and engaging said curved wall and adapted to close or clear said opening when the disk is partially rotated; said disk being provided with a partially curved slot having its outer end registerable with the outer end of the stationary slot when the apron is in open position and its inner end registerable with the inner end of the stationary slot when the apron is in closed position.

3. A dust bin comprising a container having a top wall and a curved side wall said top wall having a stationary slot extending inwardly from the periphery; said side wall having below the slot a large opening communicating with said slot; a rotary disk rotatably mounted on the top wall; an apron secured to said disk and engaging said curved wall and adapted to close or clear said opening when the disk is partially rotated; said disk being provided with a partially curved slot adapted to receive a mop handle and having its outer end registerable with the outer end of the stationary slot when the apron is in open position and its inner end registerable with the inner end of the stationary slot when the apron is in closed position; whereby when the apron is in open position said outer ends may receive the mop handle; whereupon the handle may be pushed to the inner end of the radial slot causing the closing of the apron over said opening; whereupon the handle may be shaken to agitate the mop in the barrel to remove dust therefrom; after which outward movement of the handle again causes registration of said outer ends, thus opening the front opening and allowing removal of the mop.

4. A dust bin comprising a container having a top wall and a curved side wall said top wall having a stationary slot extending inwardly from the periphery; said side wall having below the slot a large opening communicating with said slot; a rotary plate rotatably mounted on the top wall; an apron secured to said plate and engaging said curved wall and adapted to close or

clear said opening when the plate is partially rotated; said plate being provided with a curved slot having its outer end registerable with the outer end of the stationary slot when the apron is in open position and its inner end registerable with the inner end of the stationary slot when the apron is in closed position and a half-sleeve large enough to receive and guide a mop handle and having a lower out-turned flange secured to the plate around the inner end of the curved slot and positioned to cause the sleeve to engage and guide the mop handle just out of contact with the inner end edges of the slots.

5. A dust bin comprising a barrel having a top wall and a curved side wall, said top wall having an approximately radial stationary slot extending inwardly from its periphery; said side wall having below the slot a large opening communicating with said slot; a rotary disk rotatably mounted on the top wall; said disk having an apron secured on the periphery of said disk and engaging the side wall of the barrel and adapted to completely close said large opening when the disk and apron are in one position of rotation and to clear said opening when the disk and apron are in a second and open position of rotation; said disk being provided with a curved slot wide enough to receive a mop handle and having its inner end registerable with the inner end of the stationary slot when the disk and apron are in closed position and having its outer end registerable with the outer end of the stationary slot when the apron and disk are in said second and open position, whereby said outer ends may receive the mop handle; whereupon the handle may be pushed to the inner end of the radial slot causing an edge of the curved slot to cam on the handle until the handle reaches the inner end of the slots, causing partial rotation of the disk and registration of said inner ends and the closing of the apron over said large opening; whereupon the handle may be shaken to agitate the mop in the barrel to remove dust therefrom while the dust is confined in the barrel.

6. A dust bin for a mop and comprising a container having a top wall and a curved side wall said top wall having a stationary slot extending inwardly from the periphery; said side wall having below the slot a large opening communicating with said slot; a rotary disk rotatably mounted on the top wall; an apron secured to said disk and engaging said curved wall and adapted to close or clear said opening when the disk is partially rotated; said disk being provided with a slot of different shape from that of the stationary slot but having different parts registerable with the stationary slot when the apron is in open and closed positions; a guide strip secured around the side wall just below the large opening and having its upper margin slightly outwardly off-set to provide a track-groove in which the lower edge of the apron slides and is guided; a stop strip secured to the side wall near and spaced from the edge of the large opening to which the door moves when closing and having its margin nearest the opening off-set from the side wall to provide a keeper groove in which the adjacent edge of the apron is received and stopped when in closed position; said strips serving to keep the apron securely closed when the mop is being agitated in the barrel.
